UNITED STATES PATENT OFFICE.

JACOB WIENS BULLER, OF HILLSBORO, KANSAS, ASSIGNEE TO BULLER COUPLER COMPANY, INC., OF HILLSBORO, KANSAS, A CORPORATION OF WISCONSIN.

DRAFT-COUPING.

1,344,482.

Specification of Letters Patent. Patented June 22, 1920.

Application filed November 5, 1918. Serial No. 261,264.

To all whom it may concern:

Be it known that I, JACOB W. BULLER, a citizen of the United States, and a resident of Hillsboro, in the county of Marion 5 and State of Kansas, have invented a new and Improved Draft-Coupling, of which the following is a full, clear, and exact description.

Among the principal objects which the 10 present invention has in view are: to provide means for automatically releasing a movable drawn member from power means for arresting the former; to prevent wrecking of a plow or similar apparatus when the 15 progress thereof is arrested independently of the tractor means during the progress; and to simplify the construction and cheapen the cost thereof.

Drawings.

Figure 1 is a longitudinal vertical section of a coupler constructed and arranged in accordance with the present invention, the section being taken as on the line 1—1 25 in Fig. 2. The section of the coupler is shown in conjunction with a fragment of a link for uniting the coupler to the tractor, and with a clevis for uniting the coupler with an agricultural implement, the releasing 30 position of the coupler being shown by broken lines;

Fig. 2 is a top view of the same;

Fig. 3 is a vertical cross section of the coupler, the section being taken as on the 35 line 3—3 in Fig. 1.

Description.

As seen in the drawings, the coupler has a tongue 8, the upper section whereof has 40 a hook 9, which is engaged by the toe 10 of a trigger 11. The tongue 8 is provided preferably with a swell 12, which forms a rest for the heel 13 of the said trigger. A second swell 14 serves as a rest for a bridge 45 plate 15, which serves to prevent the rocking of the trigger 11 to release the toe 10 thereof.

At the rear of the swell 14, is an apron 16, the perforations 17 in which serve to 50 receive the retaining bolts 18 of the usual plow beam.

At the forward end of the tongue 8, the top 19 is reduced to form a wedge-like member which is driven under the toe 10 of the

trigger 11 when the tongue 8 is being installed in connection with the tongue retainer 20.

The trigger 11 is pivotally mounted on a shaft 21 extended between the side bars 22, of a jaw 23. The jaw 23 is united at its free end by the bridge plate 15. The bridge plate 15 has end tabs perforated to pass the bolts 24 and to be pressed by the springs 25 when the same are compressed by the nuts 26 and washers 27 disposed thereunder. 60 The nuts 26 engage threaded sections of the bolts 24. The jaw 23 is pivotally connected by the shaft 28, with the retainer 20, and adjacent the yoke arms 29 thereof. The arms 29 are suitably perforated to receive the link bolt 30, for holding the link 31, which is usually extended from a tractor or other suitable power device.

To form a recess for the tongue 8, the retainer 20 has grooves formed therein by 75 overhanging flanges 32.

From the foregoing it will be seen that the draft strain imparted to the tongue 8 and retainer 20, is borne by the trigger 11 and the hook 9. It will also be seen by 80 reference to Fig. 1 of the drawings, the point of engagement of the trigger 11 and the toe 10 thereof with the hook 9, is below the center of the shaft 21, on which the said trigger 11 pivots. As a result of this arrangement, the pulling strain tends to rotate the said trigger and to lift the jaw 23 with which the same is connected. This action is resisted by the springs 25, which bearing upon the plate 15, depress the jaw 90 and the trigger 11 connected therewith until the heel 13 bears on the swell 12.

When the draft strain becomes greater than the resistance afforded by the springs 25, the trigger 11 is rotated to a position 95 where the tongue 8 and hook 9 thereof are drawn from engagement with the trigger and with the retainer, permitting the said retainer to be carried forward by the tractor while the trailer or other implement 100 being drawn remains in arrested position.

When the obstruction which has resulted in the extra resistance of the trailer has been removed and the tractor is returned for reengagement, this is readily accomplished by inserting the tongue 8 within the retainer 20, the wedge-shaped tip 19 being forced under the toe 10 of the trigger 11,

and run forward on said retainer until said tongue 10 falls into its seat behind the hook 9.

Claims.

5. 1. A draft coupler comprising a plurality of separably connected members adapted for engaging a power member and a load member, respectively; a trigger operatively 10 uniting said members when disposed in parallel arrangement; a swinging member pivotally connected with one of said members and with said trigger for supporting the latter; and yielding means for depressing 15 the free end of said swinging member for holding said trigger in operative relation to said separable members, said yielding means embodying springs and guide bolts therefor, said bolts being movably attached to both of said separable members.

2. A draft coupler comprising an elongated retainer having separated bracket arms and a link bolt extended therebetween; a tongue slidably connected in service relation with said retainer, said tongue having a perforated apron adapted for attachment to a load member, said tongue providing a hook member; a pivoted trigger having a toe for engaging said hook member, and a heel to rest on said tongue for maintaining the service disposition of said trigger; a swinging frame for pivotally supporting said trigger, said frame being pivotally connected with said retainer; and a plurality of expansion springs operatively 35 engaging said frame and said retainer for normally maintaining said trigger in operative relation to said tongue.

JACOB WIENS BULLER.
